Filed Mar. 17, 1961, Ser. No. 96,516

Claims priority, application Germany Mar. 19, 1960
12 Claims. (Cl. 59—79)

The present invention relates generally to bands and more particularly to an expandable bracelet, especially for wrist watches.

The band is constructed of hollow links and intermediate or connecting links flexibly and expansibly connecting the hollow links together. These intermediate links are pivotally mounted against spring action. The hollow links are sleeves disposed in two layers and staggered with respect to one another in the longitudinal direction of the bracelet. The staggered upper and lower sleeves may be of either single or double link type. The connecting links comprise U-shaped clips disposed in the longitudinal openings of the links. They each have one leg inserted in the open end of a sleeve of one layer and the other leg inserted in an adjacent staggered sleeve of the other layer. A leaf spring is disposed in each sleeve of at least one layer and opposes pivoting of the connecting clips and detains the latter in the sleeve.

The band or bracelet according to the present invention differs from conventional bands due to a novel construction of the U-shaped connecting clips and their assembly with new leaf springs, and connection with the sleeves.

According to the invention, at least one of the legs of the U-shaped clips is disposed in an open end of the sleeves, and is split longitudinally to form two arms. One arm is disposed under and the other over the leaf springs which are disposed within the sleeves. The arms have an initial stress when engaging the leaf springs. The other leg of the U-shaped clip may engage and accommodate a terminal flange of the longitudinal wall of the sleeves by a recess provided near the bight portion of the clip. Alternatively this leg may engage a recess in the leaf spring by means of an inflection acting as a stop. In one embodiment of the bracelet there are separate upper and lower links and the leaf springs, acting together with the split arms of the U-shaped clips, have a cross section forming an obtuse angle. In another embodiment of the bracelet the upper and lower links are united to form a double link, and the leaf springs are plane and lie along a diagonal common to the united sleeves.

Additional objects and advantages of the present invention will become apparent upon consideration of the following description when taken in conjunction with the accompanying drawings in which:

FIGS. 1 to 7 illustrate one embodiment, namely—

FIG. 1 is a side view of one embodiment of the band illustrated in the contracted state on the left side in elevation and on the right in section taken substantially along the plane defined by line 1—1 of FIG. 2;

FIG. 2 is a horizontal sectional view taken substantially along the plane defined by line 2—2 of FIG. 1;

FIG. 3 is a side combined section-elevation similar to FIG. 1, but illustrating the bracelet in the expanded state;

FIG. 4 is a sectional view taken substantially along a portion of the plane defined by line 4—4 of FIG. 3, but illustrating only the structure disposed in this plane, except for the edge wall of the links and arm 11" which is shown to indicate its relationship with ram 11' and spring 15;

2

FIG. 5 is a fragmentary perspective of the terminal part of a link sleeve;

FIG. 6 is a perspective view of the connecting clip;

FIG. 7 is a perspective view of the leaf spring;

FIGS. 8 to 14 illustrate a second embodiment, namely:

FIG. 8 is a side combined elevation-section similar to FIG. 1 but of another embodiment illustrated in the contracted state with the right side taken substantially along the plane defined by line 8—8 of FIG. 9;

FIG. 9 is a horizontal section view taken substantially along the plane defined by line 9—9 of FIG. 8;

FIG. 10 is a combined elevation-section illustrating the band in the expanded state;

FIG. 11 is a sectional view taken substantially along the plane defined by line 11—11 of FIG. 10;

FIG. 12 is a perspective view of the connecting clip of the second embodiment;

FIG. 13 is a plan of one form of the leaf spring for the second embodiment, and

FIG. 14 is a plan of another form of the leaf spring for the second embodiment.

The first embodiment (FIGS. 1 to 7) of the expandable bracelet has two separate superposed layers or rows 1, 2 of links 3, 4 in the form of sleeves having a rectangular cross section. The links are staggered with respect to one another in the longitudinal direction of the band. From the longitudinal walls 5 of the lower layer 2 of the links 4, short terminal flanges 6 are bent to face inwardly toward each other at right angles to be disposed in openings 7 (FIG. 5). The connecting links are U-shaped clips 8' (FIG. 6) of spring material having a rectangular cross section. Each clip is formed from a single strip of material and includes a bight portion 9, a leg 10 bent at right angles with the bight portion, and another leg including two arms 11' and 11", each about half as wide as leg 10 and bent at right angles from the other end of the bight portion 9. To form the arms, the portion of the strip used to form them and an adjacent part of the bight portion are split by a longitudinal slit 12. The arms 11' and 11" are bent off at bight portion 9, at different distances from leg 10. The difference between these distances corresponds to the thickness of the metal sheet of leaf spring 15. In addition, the two arms 11' and 11" are prestressed, bent somewhat towards one another, and provided at their ends with bevels 13 extending from the outside to the inside. On the same side of the clip 8' where higher arm 11' is disposed and underlying same, leg 10 has a rectangular recess 14 adjacent bight portion 9. The third part of this embodiment of the bracelet is the leaf spring 15 bent so that its legs form an obtuse angle in cross section (FIG. 7).

Before bending the flanges 6 into opening 7, the leaf springs 15 are inserted into the links 3 of the upper layer 1. The connecting clips 8' are inserted with leg 10 and the two arms 11', 11" through the openings 7 of the links 3 and 4 of the two layers 1 and 2 in such a way that the lower arm 11" engages the leaf spring 15 on its lower surface, while the other arm 11' engages its upper surface. The insertion of the leaf spring 15 between the arms 11', 11" against their spring action is facilitated by the terminal bevels 13. This causes an initial stress of the arms 11', 11", brought about by their mutual bending, and the cooperation of the leaf spring 15. Thus, the clip 8' is biased in the direction toward that side of the clip which has the higher arm 11'. The clip 8' is pivoted while in engagement with the flange 6 of the longitudinal wall of the lower links 4 by the recess 14 in its leg 10 and is detained in the links 3 and 4. The links 3 of the upper layer 1 and the links 4 of the lower layer 2 are pivotally connected to the connecting clips 8' and thus may move toward one another in the longitudinal direction of the

band, thereby contracting the bracelet, and can be expanded against the action of the arms 11', 11" and leaf spring 15 biasing the links toward each other.

The second embodiment (FIGS. 8 to 14) of the bracelet is constructed of double links 16 consisting of two sleeves 16', 16" of substantially square cross section and offset with respect to one another. The sleeves 16' form the upper layer 17 and sleeves 16" form the lower layer 18 of the bracelet, the sleeves of which are offset from those of layer 17. The double links 16 are formed by bending a rectangular metal sheet. A central bending point 19 of the sheet lies at the connecting point of the double links, while the terminal edges 20, 21 of the sheet freely oppose the bending point 19. The flanges 22, 23 of the double links 16 which are the ends of the rectangular metal sheet, lie adjacent bending point 19 and may be disposed obliquely to the longitudinal direction of the band. The connecting links of the second embodiment are also U-shaped clips 8" (FIG. 12) with a bight portion 9, leg 10' and two arms 11', 11", offset in height and bent towards one another, and terminal bevels 13. The leg 10' has an inflection 24 forming an angled portion thereon. In this embodiment, plane leaf springs 25' or 25" (FIGS. 13 and 14), rectangular in outline, are used, whose width substantially corresponds to the common diagonal running through the two sleeves 16' and 16" of the double link 16. These springs have rectangular recesses 26, in the same longitudinal side in spring 25' (FIG. 13) and in opposite longitudinal sides in spring 25" (FIG. 14), and two bores 27 in their center for achieving a smooth spring action.

The leaf springs 25' are inserted longitudinally into the double links 16 in alignment with the diagonal of the link sleeves 16', 16" so that their recesses 26 are in the lower sleeves 16". The connecting clips 8" are inserted with their leg 10 and arms 11', 11" extending through the side openings of the double link 16. The upper half of the leaf spring 25' is gripped by the two arms 11', 11" along its top and bottom surfaces, respectively. Due to the initial stress of these two arms and their cooperation with the leaf spring 25', the clips 8" are biased in the direction toward that side of the clip which has the higher arm 11'. The clip 8" is brought into engagement with the recess 26 of the leaf spring 25' by its deflection 24 forming the angled portion when being inserted into the lower sleeve 16" of the link, and is pushed into engagement therewith and secures the connection of the three band components, double link 16, connecting clip 8, and leaf spring 25'. The double links 16 are contracted in the longitudinal direction of the band, thereby shortening the bracelet. Yet the bracelet may be expanded against the action of the arms 11', 11" and leaf spring 25', the double links 16 thereby moving away from one another, which is facilitated, as is their gliding into one another, by the oblique center flanges 22, 23. If the leaf springs 25" (FIG. 13) with recesses on the opposite longitudinal side are used, the connecting clips 8 are accordingly arranged at the two edge sides of the bracelet inversely regarding their leg 10' and their arms 11', 11".

It will be understood that the above description of the present invention is susceptible to various modifications, changes, and adaptations, and the same are intended to be comprehended within the meaning and range of equivalents of the appended claims.

I claim:

1. An expansion band, comprising, in combination: a plurality of body links arranged to form two layers of sleeves, said links being staggered with respect to each other; a plurality of leaf springs disposed one in each of the sleeves of at least one layer; and a plurality of connecting links in the form of U-shaped clips, said connecting links connecting each said body link to a respective next adjacent body link, each said connecting link hav-

ing one leg disposed in a sleeve of one layer in one body link and the other leg disposed in an adjacent sleeve of the other layer in an adjacent body link, each of said leaf springs having generally oppositely facing surfaces, 5 a portion of one of said surfaces bearing against its associated body link, said clips each having one leg split longitudinally to form arms disposed one against each of said surfaces of its associated leaf spring, the one of said arms the closest to said surface portion bearing against the other said surface of its associated leaf spring, said arms having an initial stress directed against the leaf spring, whereby the links are biased toward each other.

2. The expansion band of claim 1, wherein said arms are connected to the bight portion of the clip at positions spaced apart a distance corresponding to the thickness of the leaf spring, the arms being bent toward each other to achieve their initial stress.

3. The expansion band of claim 1, wherein the ends of said arms are beveled inwardly, whereby when pushed onto the leaf spring said arms are guided one to each side.

4. The expansion band of claim 1, wherein the body links are independent of each other, and each leaf spring has two legs at an obtuse angle in cross section, one of 25 said legs being connected to each leg of each leaf spring.

5. The expansion band of claim 1, wherein said body links are open ended sleeves and those in one layer have terminal portions of their longitudinal walls bent into the sleeve openings, the other arm of each clip having a 30 recess at its edge opposing the longitudinal wall of the sleeve near the bight portion of the clip for accommodating said terminal portions.

6. The expansion band of claim 1, wherein the body links are double sleeves including one from the upper 35 layer and one from the lower layer, each leaf spring being planar.

7. The expansion band of claim 1, wherein each leaf spring has a recess, and the other leg of each connecting link is provided with an inclined portion and an offset portion which fit into said recess.

8. An expansion bracelet, comprising, in combination: a plurality of main links defining sleeves disposed in two rows, said links being staggered with respect to each other; connecting links each pivotally connected to a main link sleeve of each row; leaf springs for the connecting links, one leaf spring being disposed in each sleeve of at least one row, each connecting link being generally U-shaped and having one leg pivotally connected to the sleeve of a main link in one row and another leg pivotally connected to the sleeve of another main link in another row, one leg of each connecting link being resilient and split by a longitudinal slit thereby to form two arms which are offset from each other in one direction transversely of said slit, said arms when unstressed being spaced apart for at least a portion of their lengths in another direction transversely of said slit a distance less than the thickness of the leaf spring, said arms resiliently engaging said leaf spring one on each side, said arms extending over said sides and thereby being stressed and biasing the connecting links and thus the sleeves toward each other, and means on the other leg of each connecting link pivotally cooperable with the sleeve of one of said main links whereby the bracelet may be expanded against the spring action of the stressed arms and the leaf spring, said bracelet including means for maintaining said connecting links in their assembled positions.

9. The expansion bracelet of claim 8, wherein said arms are connected to the bight portion of each connecting link at different distances from said other leg and are bent toward each other and stressed when engaging said leaf spring.

10. The expansion bracelet of claim 8, wherein said means includes an angled portion on said other leg disposed in a recess in another of said leaf springs.

11. The expansion bracelet of claim 8, wherein said means includes a notch in said other leg accommodating a flange on the cooperating sleeves.

12. In an expansion band including hollow links, intermediate links flexibly and expansibly connecting the hollow links together, the hollow links defining sleeves disposed in two layers, the hollow links being staggered with respect to each other, the intermediate links being U-shaped clips having one leg disposed in a sleeve of one layer and the other leg disposed in an adjacent sleeve of the other layer, a plurality of leaf spring means disposed one in each of the sleeves of one layer for biasing the hollow links toward each other, and the band including means for maintaining said connecting links in their assembled positions, the improvement that: said clips each has one leg which is resilient and split by a longitudinal slit to form two arms which are offset from each other in one direction transversely of said slit, said arms

when unstressed being spaced apart for at least a portion of their lengths in another direction transversely of said slit a distance less than the thickness of the leaf spring means, and said arms are disposed one on each side of each leaf spring means and thus have an initial stress directed against each leaf spring means.
